UNITED STATES PATENT OFFICE.

MORRIS LEVIN, OF PROVIDENCE, RHODE ISLAND.

DESIGN FOR A DISPLAY CABINET.

Application filed March 30, 1926. Serial No. 17,114. Term of patent 14 years.

To all whom it may concern:

Be it known that I, MORRIS LEVIN, a citizen of the United States, residing in the city of Providence, county of Providence, and State of Rhode Island, have invented a new, original, and ornamental Design for a Display Cabinet, of which the following is a specification, reference being had to the accompanying drawing, forming a part thereof.

The figure is a perspective view of a display cabinet, illustrating my new design.

I claim:

The ornamental design for a display cabinet, substantially as shown.

MORRIS LEVIN.
